UNITED STATES PATENT OFFICE

140,600

DESIGN FOR AN ESCALATOR BALUSTRADE

Otto Hohnecker, Toledo, Ohio, assignor to The Haughton Elevator Company, Toledo, Ohio, a corporation of Ohio

Application January 11, 1945, Serial No. 117,381

Term of patent 14 years

(Cl. D13—7)

To all whom it may concern:

Be it known that I, Otto Hohnecker, a citizen of the United States and resident of Toledo, in the county of Lucas and State of Ohio, have invented a new, original, and ornamental Design for an Escalator Balustrade, of which the following is a specification, reference being had to the accompanying drawing, forming a part thereof.

In the drawing, Fig. 1 is a top plan view of an escalator balustrade showing my new design; Fig. 2 is a side elevation, and Fig. 3 a view of either end thereof.

The dominant features of the design reside in the shaded end portions shown in the drawing.

I claim:

The ornamental design for an escalator balustrade, substantially as shown and described.

OTTO HOHNECKER.
